Specification of Letters Patent.

Patented Feb. 7, 1922.

Application filed March 5, 1919. Serial No. 280,724.

To all whom it may concern:

Be it known that I, WILLIAM F. HELMOND, a citizen of the United States, residing in Hartford, in the county of Hartford and State of Connecticut, have invented certain new and useful Improvements in Type-writing Machines, of which the following is a specification.

This invention relates mainly to the carriages of typewriting machines of the kind in which a platen is carried by a platen frame which is shiftable upon the carriage, to enable upper and lower-case letters to be printed.

Since it is a necessity that the parts move with utmost freedom at the shifting operation, it has been the practice to mount the platen frame loosely. This has interfered with accuracy of printing, made it difficult to fit the platen frame properly to the carriage, and rendered the operation noisy. The shifting is effected by the pressure of the operator's finger upon a key on the keyboard, and hence must not be burdensome, while the operation must be very rapid in order to meet the demand for rapid type-writing. The problem is further complicated by the necessity of making all of the parts very light, since the typewriter carriage must move and come to rest between type impressions, which are often made at the rate of fifteen to twenty per second. The problem is to secure accuracy of writing and ease of operation at such high speed, by means of mechanism which must be lightly constructed, although carrying a heavy platen.

Certain of the objects of my invention are to reduce the cost of producing the parts, to render them easy to assemble by comparatively unskilled workmen, to eliminate the necessity of fitting parts accurately in manufacture, to secure increased freedom of movement of the platen and platen frame at the case-shifting operation, and to accomplish these results without increasing the weight of the platen frame and carriage.

Difficulty is also experienced with creeping of the work-sheets upon the platen, which is found to be due to some extent to the shocks which the carriage receives in rapid operation, particularly when the carriage is violently arrested at the conclusion of its return stroke, or at the conclusion of a long run of the carriage when tabulating.

This creeping is due to the accumulation of minute relative displacements which occur between the work-sheet and the platen, when the carriage receives such shocks; and they occur largely because of the looseness of the platen in the platen frame, and of the platen frame in the carriage, which permit minute endwise independent movements of the platen. It is one of the objects of the invention to overcome this difficulty.

The present improvements are shown as applied to the carriage of an Underwood typewriting machine. It has been customary to mount upon the rectangular main carriage a platen frame built up of sheet-metal, and to guide said platen frame in its up-and-down movements by means of arms or so-called "lift hooks," mounted upon a rock shaft which is journaled in the main carriage. It has been found necessary to make the platen a little loose endwise in its bearings in the platen frame, and the platen frame must fit loosely endwise in the rocking frame, and the rocking frame must fit loosely endwise in its bearings upon the typewriter carriage; all of these loose fittings being necessary in order to permit the necessary free movement. To reduce the liability of both platen and frame to shake, and the resultant inaccuracy of printing, it has been the practice to provide a vertical guide upon the carriage for the platen frame, this guide usually engaging the platen axle.

The mounting of said rock shaft in the carriage has also usually been such as to permit slight forward and backward adjustment of either end of the frame, and hence of the platen, so as to bring the printing surface thereof into exact parallelism with the direction of travel of the carriage, and also into exact position for receiving the blows of the types. It is the practice in said Underwood machine to allow the type-bars to contact with a so-called "stop ring" or anvil in the form of a metal segment, whereby the type-bars are positively arrested near their fulcrum ends at the instant of printing. This makes it desirable to provide for delicate forward and backward adjustments of the platen, in order to insure the desired strength of type impressions.

This forward and backward adjustment of the rocking frame is secured by improved

65

means in the present invention, in connection with means for eliminating all play endwise between the rocking frame and the carriage frame, while permitting increased 5 freedom of movement and at the same time avoiding noise.

In order to secure such forward and backward adjustment, said rock shaft is hinged to eccentric bushings which are mounted in 10 the carriage frame. Each bushing may be turned independently of the other, so as to adjust either end of the platen forwardly or backwardly.

The rocking frame may be fitted tightly 15 against any possible endwise play, while swinging quietly and with greater freedom than has heretofore been possible. To this end said rock shaft is mounted in the carriage frame by means of ball-bearings, 20 and said eccentric bushings are made relatively adjustable axially against elements of said bearings so as to take up all end play.

To overcome the difficulty of fitting a 25 loose, weak platen frame properly to its "lift hooks" or rocking frame, so that there will be freedom of motion, and without looseness and consequent noise and inaccuracy of printing, I take two steps, one 30 of which is to make the platen frame oversize, say one-sixteenth of an inch too long to fit between the "lift hooks" or rock arms. In assembling the parts, these arms are wedged or sprung apart sufficiently to permit 35 the platen frame to be set between them. This not only eliminates endwise play between the platen frame and the "lift hooks" with its shake and noise, but also renders it practicable to assemble these parts quickly 40 and inexpensively, even if the platen frames are not manufactured exactly alike, some being longer than others, since the springing of the "lift hooks" together will compensate for any slight variations in length of the 45 platen frame.

The second step is to connect the platen frame to the "lift hooks" by means of such ball bearings that the platen frame will be about as firm as if made solid with the 50 carriage, but will be permitted to shift up and down with even more freedom than has been found practicable heretofore. In other words the construction of the rocking frame and the pivotal connections between the rock 55 arms thereof and the platen frame are such as to cause the gripping or compression of the frame between said rock arms while permitting the utmost freedom of pivotal movement.

60 Another feature of the invention relates to improved means for mounting the platen in the platen frame, particularly with a view to avoiding endwise and other play of the platen, and consequent imperfection in the 65 printing, with liability of creeping of the

work-sheet upon the platen. An object of this portion of the invention is to support the platen rigidly while permitting it to rotate freely. Another object is to reduce the burdensome cost of altering the length of 70 each platen to fit it to its frame. I form each platen frame end with an opening and force a headed bearing ring therein. Within the bearing ring is formed a V-groove to receive a set of balls, which run upon 75 cones through which the platen axle extends. Each pair of cones is provided with a coupling tube having a head at one end and spun over at the other end to confine and take up play of the balls; the whole ball 80 bearing being thus confined permanently in the platen frame end, so that in order to mount a platen it is only necessary to pass the platen axle through the platen and the platen-frame ends. The platens may be 85 made all the same length, each being a little too short to fit between the platen frame ends. At one end a bushing is threaded into the platen head, so that it may be screwed out, thereby in effect elongating the platen 90 until it fits between the platen frame ends, so as to eliminate endwise shake of the platen. The platen is thus rigidly supported upon the main carriage frame, but may be freely raised and lowered and freely rotated. 95 To maintain the platen of the proper length, I provide a series of very thin spacing washers, which are inserted between the head of the bushing screw and the hub of the platen. As many of these may be employed as are 100 necessary to fill the space between said head and said hub. The platen may thus be quickly and cheaply fitted.

In the Underwood machine, it has been the practice to have each end of the platen 105 frame rest in two places upon the carriage, in lower-case or normal position of the platen.

Owing to the weakness of the platen frame and the impracticability of manufacturing all frames exactly the same, it has been found difficult to bring the platen frame to proper rest upon the carriage, making it necessary to bend the frame here and there, which is slow work and demands the 110 skill of a specialist.

One of the objects of the invention is to reduce this difficulty and simplify the operation of fitting the platen frame to the carriage, and to seat the platen frame more 115 firmly, and avoid liability of noise, which has heretofore occurred because of the inequality of the fitting of the platen frame rests or feet to the top of the carriage. In carrying out this feature of the invention, 120 the front feet or rests of the platen frame are formed as heretofore, and consist of one tongue extending down from each platen frame end. The customary rear platen rests are omitted; but I arrange to support the 125 130

platen frame in the rear by means of a single rest which is fixed to the platen frame at its middle portion, and I provide upon the rear carriage-bar a block or support, 5 upon which this third rest may directly rest. With the parts constructed in this way, the platen frame will be found in many instances to fit properly upon the carriage at all three resting points; but in case the 10 platen frame should have become warped from any cause, so that one of the forward rests does not come to a proper bearing upon the carriage, the platen-guiding arm at the end of the platen frame may be bent a trifle up or down to bring the rest at that 15 end of the platen frame into proper position; or the platen frame end itself may be bent a trifle. This is a simple operation, and the work is limited to correcting the 20 position of only one of the rests, since the other two will not need attention; whereas, in the machine as heretofore constructed, it frequently happened that two of the rests had to be corrected. Notwithstanding such 25 correction, there was likely to be noise or rattling due to the loose mounting of the platen frame; whereas, in the present construction, only one rest ever needs to be corrected, and the platen frame always rests 30 lightly on the carriage frame without liability of rattling at any of the three bearing points.

Other features and advantages will hereinafter appear.

35 In the accompanying drawings,

Figure 1 is a sectional, side elevation of an Underwood front-strike typewriting machine, illustrating certain of the present improvements.

40 Figure 2 is a perspective view of the platen frame, showing particularly the improved connection between the guide-frame, platen frame and carriage, and also the improved manner of mounting the platen in 45 the platen frame.

Figure 3 is a plan to show the relation between the platen frame, guide-frame and carriage.

Figure 4 is a sectional, front elevation of 50 the rocking frame which guides the platen frame, showing particularly the details whereby said rocking frame is rigidly hinged upon the carriage.

Figure 5 is a perspective view of a ball-bearing unit employed in connecting the rocking guide-frame to the carriage.

Figure 6 is a perspective of a threaded bushing or sleeve seen in Figure 4 and employed in hinging the rocking frame upon 60 the carriage.

Figure 7 is a sectional side elevation to illustrate the connection of the rocking frame.

Figure 8 is a front elevation, partly in

section, to illustrate the manner of mounting 65 the platen in the platen frame.

Figure 9 is a part section of a side elevation to illustrate the ball-bearing construction of the platen frame.

Figure 10 is a sectional side elevation to 70 show the ball-bearing connection between the platen frame and one of the guide-frame arms.

Figure 11 is a perspective view of a nut or bushing threaded into the hub of one of the 75 platen heads, for adjusting the length thereof. This figure also shows two thin spacing washers or fillers used in connection with said nut.

Figure 12 is a perspective view upon a 80 large scale, illustrating means for regulating the length of the platen and for mounting the same in the platen frame.

As usual in the Underwood typewriting machine, type-bars 20, operated by key-levers 21, strike against the front of a platen 22, which is shiftable up and down to enable different types 23 to print, there being a shift key 24 which is usually mounted upon a lever 25, which operates an arm 26 pendent 90 from a rock shaft 27 and forming part of a lift frame 28, which also includes a horizontal rail 29 upon which runs a roll 30, said roll mounted upon the lower portion 31 of a platen frame, which is thus shifted 95 up and down together with the platen 22.

Said platen frame is hinged to a carriage frame 32 running upon stationary front and rear tracks 33, 34. The hinge-rod is seen at 35, and is carried by ears 36, 37 which 100 rise from the rear bar of the rectangular carriage 32. From this hinge-rod 35 extend forwardly guide-arms 38, which, at their forward ends, are fitted to gudgeons 39 provided upon the ends 40, 41 of the platen 105 frame; said platen frame also comprising a paper-guiding shelf 42 in rear of the platen and a bar 43 which connects said ends.

The vibrating arms or "lift hooks" 38 110 have bosses or hubs 44, which are fixed upon the ends of said hinge-rod 35; and pairs of ball-bearing cones 45 are fixed upon said hinge-rod or rock-shaft, and set up against these bosses. In the carriage ears are 115 mounted bushings 46, 47, the outer end of each bushing having a head 48 in which is formed an interior V-groove 49, these grooves completing the raceways for bearing balls 50.

At Figure 4, the left-hand bushing 46 is shown as set up against the carriage ear 36, and as clamped firmly therein by means of a screw 51, which connects the portions into which the ear is split. The right-hand bushing 47 is shown as contained within a bushing 52, which is threaded through the carriage ear 37, the head 53 of this bushing 120

52 being formed for engagement by a wrench, whereby it may be turned out as far as required, in order to take up endwise play of the hinge-rod 35; and this bushing 5 52 is clamped by a screw 51 in the same manner as the left-hand bushing 46, so as to retain 52 at the point to which it is adjusted. It will be seen that the screw bushing 52 and the main bushings 46, 47 are rigid 10 with the carriage ears 36, 37, and that the cones 45 are rigid with the hinge-rod; and that owing to the presence of the bearing balls 50, it becomes feasible to spread or separate the main bushings 46, 47 until the 15 rocking structure is tight upon the carriage, so that all liability of shake is eliminated, together with the noise, while there is more freedom of motion than practicable in the loosely-fitted bearings heretofore found 20 necessary.

Said main bushings 46, 47 are constructed and mounted for the purpose of adjusting the hinged frame 35, 38, together with the platen frame and platen, forwardly and backwardly at either end, the extent of adjustment being indicated by the dot-and-dash lines at Figure 7. The axis of hinge-rod 35 is eccentric to the bearings in the carriage ears 36, 37, so that by revolving the main 25 bushings 46, 47 in said bearings, forward or rear adjustments of the platen frame and platen may be secured. The rotation of the bushings may be effected by a wrench applied to the flattened portions 53^a upon ends 30 of the bushings which project through the carriage ears. The bushings are secured against rotation by tightening the screws 51. The screw bushing 52 is split from end to end, and compressible by the screw 51, so 35 that it may be caused to clamp the main or eccentric bushing 47 to hold the latter against rotation. The threads in the screw bushing hold said bushing 47 against being forced to the left under the pounding action 40 of the carriage and platen frame. The connection of the hinged frame to the carriage is solid and not subject to becoming loosened, while freedom of action is secured, and noise is eliminated.

50 The composite bushing, comprising the separate bushings 47, 52, provides a simple and practical means for adjusting the spacing of the cones to take up end play, and for adjusting the alignment of the platen, 55 each independently of the other, since each of the separate bushings may be independently rotated to effect its respective adjustment. It will be obvious, however, that the means for effecting one of these adjustments 60 may be omitted if desired. For example, the forward and backward adjustment of the platen may be omitted, or otherwise provided for, while still retaining the adjustment for taking up end play.

65 Each of the main or eccentric bushings,

with its balls and cones, may be constructed as a unit for assembling into the machine or detachment therefrom. To this end, the cones are mounted upon a short tubular coupling or lining 53^b, which is formed with 70 an inner head or flange 54, and at its outer end is spun over the outer cone at 55, to take up the play of the balls 50 and to hold the cones and balls permanently in the main bushing head 48, thus forming a unit, as at 75 Figure 5. A space is left at 56 between the cones in each pair, to permit the cones to approach each other at the operation of spinning or forcing over the flanges 55 taking up the play of the balls, and also to permit 80 their further approach to take up wear in the bearings.

It will thus be seen that the parts may be inexpensively made and cheaply assembled, and that the vibrating frame and 85 the carriage may be quickly brought to a tight fit and secured against coming loose, thus eliminating much of the cost of manufacture of a combined carriage and shifting frame.

90 At their forward ends, the vibrating arms or "lift hooks" 38 are fitted to gudgeons or stub shafts 39 mounted in the ends 40, 41 of the platen frame. Each of said ends has a large hole 56^a, surrounded with a flange 56^b, 95 and a ring forming an annular bearing 57 is inserted in this hole, said bearing having a head 58 which abuts against the flange or rim 56^b. The bearing is exteriorly grooved, undercut or tapered at 59 from its inner 100 face, and after the insertion of said bearing, said flange 56^b is forced into said undercut or taper 59, thus permanently securing the bearing in the end of the platen frame. Said bearing is interiorly grooved at 60 to 105 contain a set of bearing balls 61; and cooperating cones 62 for said balls are held together upon a reduced shank 63 upon said gudgeon 39, one cone abutting against the body of the gudgeon, and the other cone being retained by a flange 64 upon the inner end of the shank 63, which flange is turned out after the cones and balls are assembled, thereby taking up the play of the balls; 110 while a space is left at 65 between the cones to permit them to approach each other. The platen frame, with the gudgeons and ball bearings, thus forms a unit, since the gudgeons are permanently retained. The gudgeons may be bored centrally to reduce 115 weight, and also to facilitate the turning over of the cone-confining flanges 64.

120 The forward ends of the vibrating guide-arms 38 are provided with bearings at 66 to fit the gudgeons 39, and this may be a tight 125 fit, since the gudgeons may be rigid with the arms and still turn freely, owing to the use of the ball bearings. Preferably each arm 38 is provided with a detachable cap 67 to fit over the gudgeon.

In assembling the platen frame, the vibrating guide-frame and the carriage, the platen frame is made oversize, that is, about one-sixteenth of an inch too long to insert 5 between the vibrating arms 38. Said arms are then forced apart by any suitable means, so as to permit the introduction of the platen frame therebetween. The arms are then permitted to close upon the platen frame, holding 10 the same permanently in a strong grip. This normal springy condition of the vibrating frame is indicated diagrammatically by the slight curvature of the hinge-rod 35 at Figure 3. The gudgeons 39 are provided 15 with flanges 68, against which the arms 38 may press. The use of the balls 61 permits this tight but elastic relationship between the vibrating guide-frame and the platen frame, and at the same time increases the 20 ease and speed of shifting action of the platen frame. Since the platen frame and vibrating frame are normally tensioned, the flexing or warping of these frames, by reason of shocks received during the carriage 25 movements, is greatly reduced. The platen frame 40, 41, 42, 43 is practically rigid with the carriage frame, except that it is shiftable freely up and down, and it is firmly held against sidewise or other distortion, which 30 makes for both accuracy of printing and speed and quietness of operation, as well as reducing the liability of the sheet to slip on the platen, and renders unnecessary the sliding platen-frame guide heretofore used, 35 since the platen frame is under control and not subject to being jarred out of place at any time during the typing operations, especially in a direction longitudinal of the platen, and hence the impression of each 40 type upon the paper carried by the platen is caused to be exactly in the desired relation to the impressions of other types, thus insuring evenness of printing or spacing.

The platen is also mounted rigidly with 45 the platen frame, and controlled against endwise shake, notwithstanding the relatively heavy weight of the platen and the light construction of the platen frame. To secure this rigid endwise control of the 50 platen, and yet permit it to rotate freely, and eliminate noise, there are employed ball bearing devices, each of which comprises an annular bearing in the form of a ring 69 set into a hole 70 provided in the platen 55 frame, the bearing ring having upon its inner end a head 71. An outer flange or rim 72 surrounds the hole, to form a broad support for the bearing, which is forced into said hole from the inside of the platen 60 frame, to bring said head 71 firmly against the end of the platen frame. This bearing 69 is provided with an interior V-groove 73 in which run bearing balls 74; and cones 75 are used to complete the raceways for the 65 balls. These cones are connected in each

case by a tube or lining 76, in the manner already described, each tube 76 having formed thereon at one end a head 77, and being rolled out at the other end to form a flange 78 to confine the spaced cones and take up 70 the play of the balls. Thus the platen frame with the gudgeon bearings and the platen axle bearings forms a unit, the ball bearings being permanently confined therein. If desired, however, the ball bearings for the 75 platen may be forced inwardly to disconnect them from the platen frame. Said ball bearings are normally prevented from being displaced by the presence of the platen, which entirely fills the space between the 80 bearings, so that the bearing at one end cannot be forced towards the bearing at the other end, and hence is locked in the platen frame. The flanges 56^b, 72 may be formed integral with the platen frame ends. 85

At one end the platen may be provided with the usual head 79 having a hub secured by a screw 80 to the platen axle. At the other end of the platen a bushing 81 may be threaded into the hub 82 of a platen head 83; 90 and this bushing may have a suitably formed head 84, which may be turned outwardly by means of a wrench, having the effect of lengthening the part of the platen surrounding the platen axle, so that the 95 platen fits closely between the inner cones 75 of the ball-bearing structures. This fit may be so tight as to spring the ends of the platen frame a trifle, said platen frame being already sprung or tensioned, inwardly 100 by the constant pressure of the guide-arms 38 towards each other, as already explained. The heavy platen is thus held successfully against endwise shake at the typing operation, notwithstanding the weakness of the 105 sheet-metal platen frame. This tightness of the platen and the platen frame, and between the guide-arms and the platen frame, does not result in binding at the bearings, because the balls overcome the tendency to 110 bind. The platen is therefore rigid with the main carriage frame 32, except that it may rotate freely and also shift freely up and down. This makes for quietness and accuracy, and minimizes or avoids the liability of 115 the sheet to creep or skew upon the platen.

Very thin spacing washers 85 may be filled in between the head 84 of the bushing and the end of the platen hub 82. More or as many washers may be employed as required, in adapting the platen to different platen frames, which may vary a trifle in measurement. These spacing washers 85 may be inserted in the following manner. The platen may first be placed between the 120 roller-bearings and the axle slipped through said bearings and platen. The bushing 81 may then be rotated in the direction such as to increase the effective length of the platen sufficiently to effect the desired tight fit, re- 130

moving all end play between the platen and its frame. Measurement may then be made of the space between the head 84 and the hub 82 of the platen head 83 to determine 5 the number of washers 85 necessary to fill the gap. The axle may then be withdrawn, the platen removed, and the bushing 81 separated therefrom. The number of washers previously determined upon may then be 10 slipped over the bushing 81 against its head 84, and said bushing inserted and screwed firmly into the platen end to the extent permitted by said washers. The adjusted length of the platen having been in this 15 manner effected, the platen may be forced to its place between the roller-bearings in the platen frame and the axle again inserted and secured in place by means of the set-screw 80. These spacers prevent the bushing 20 81 from turning in, and the platen-frame ends prevent it from turning out.

The platen-frame has front feet 86 which normally, or in lower-case position, rest upon the tops of the end bars of the carriage frame 32; and upon the carriage are 25 also provided the usual adjustable stops 87, which are engaged by shoulders 88 formed upon the platen-frame ends, to limit the upward shift of the platen frame for writing 30 capital letters. Besides the feet 86 on the ends of the platen frame, the latter is provided with a novel foot 89 at its rear middle portion, said foot attached to the cross-bar 43 which forms a portion of the platen frame, 35 and resting upon a finished block 90 formed at the middle of the rear carriage-bar. Thus the platen frame normally rests upon three supports; and if it is noticed in assembling the parts that either of the front feet 40 86 fails to rest properly upon the carriage, it will only be necessary to bend the platen frame a trifle to bring the foot down into proper contact, the other front foot and the rear foot not requiring attention. Therefore, 45 the matter of adjusting the platen frame to its proper normal position of rest upon the carriage is much simplified and cheapened, and the machine is rendered more satisfactory, since the constant liability 50 of noise, due to chattering of any one of the four feet heretofore used, is avoided.

Variations may be resorted to within the scope of the invention, and portions of the improvements may be used without others. 55 Having thus described my invention, I claim:

1. The combination with a carriage and a platen frame therefor, of a rocking frame connecting the carriage to the platen frame, 60 said rocking frame comprising a hinge-rod or shaft, arms fixed upon the ends of said shaft and connected to said platen frame, bushings mounted upon the carriage and provided with interior grooves, balls run-

ning in the grooves, cones upon said shaft to 65 hold the balls, and means to effect relative adjustment of said bushings to make a tight fit between the rocking frame and the carriage.

2. The combination with a carriage and 70 a platen frame therefor, of a rocking frame connecting the carriage to the platen frame, said rocking frame comprising a hinge-rod or shaft, arms fixed upon said rod and connected to said platen frame, bushings 75 mounted upon the carriage and having heads provided with interior grooves, balls running in the grooves, and cones upon said hinge-rod to co-operate with the balls.

3. The combination with a carriage and a 80 platen frame therefor, of a rocking frame connecting the carriage to the platen frame, said rocking frame comprising a hinge-rod or shaft, arms fixed upon said rod and connected to said platen frame, bushings mount- 85 ed upon the carriage and having heads provided with interior grooves, balls running in the grooves, cones upon said hinge-rod to co-operate with the balls, ears upon the carriage in which said bushings are mount- 90 ed, one of said heads abutting against the ear, and means for effecting adjustment in axial direction of the other of said bushings.

4. The combination with a carriage and a platen frame therefor, of a rocking frame 95 connecting the carriage to the platen frame, said rocking frame comprising a hinge-rod or shaft, arms fixed upon said rod and connected to said platen frame, bushings mounted upon the carriage and having heads pro- 100 vided with interior grooves, balls running in the grooves, cones upon said hinge-rod to co-operate with the balls, ears upon the carriage in which said bushings are mounted, one of said heads abutting against the ear, 105 and means for effecting adjustment in axial direction of the other of said bushings, said adjusting means comprising a third bushing threaded in one of said carriage ears and surrounding the main bushing, and in 110 engagement with the head thereof to effect axial adjustment.

5. The combination with a carriage and a platen frame therefor, of a rocking frame connecting the carriage to the platen frame, 115 said rocking frame comprising a hinge-rod or shaft, arms fixed upon said rod and connected to said platen frame, bushings mounted upon the carriage and having heads provided with interior grooves, balls run- 120 ning in the grooves, cones upon said hinge-rod to co-operate with the balls, ears upon the carriage in which said bushings are mounted, one of said heads abutting against the ear, means for effecting adjustment in 125 axial direction of the other of said bushings, said adjusting means comprising a third bushing threaded in one of said carriage ears

and surrounding the main bushing, and in engagement with the head thereof to effect axial adjustment, and means for clamping said grooved bushings and said threaded bushing.

6. The combination with a carriage and a platen frame therefor, of a rocking frame connecting the carriage to the platen frame, said rocking frame comprising a hinge-rod or shaft, arms fixed upon said rod and connected to said platen frame, bushings mounted upon the carriage and having heads provided with interior grooves, balls running in the grooves, cones upon said hinge-rod to co-operate with the balls, ears upon the carriage in which said bushings are mounted, one of said heads abutting against the ear, means for effecting adjustment in axial direction of the other of said bushings, said 10 adjusting means comprising a third bushing threaded in one of said carriage ears and surrounding the main bushing, and in engagement with the head thereof to effect axial adjustment, and means for clamping said 15 grooved bushings and said threaded bushing, said threaded bushing being split from end to end to permit it to be clamped upon the grooved bushing therewithin.
7. The combination with a carriage and a platen frame therefor, of a rocking frame connecting the carriage to the platen frame, said rocking frame comprising a hinge-rod or shaft, arms fixed upon the ends of said shaft and connected to said platen frame, bushings mounted upon the carriage and provided with interior grooves, balls running in the grooves, and cones upon said shaft to hold the balls, said grooved bushings being mounted eccentrically of the 20 hinge-rod, and being rotatable to permit adjustment of the rocking frame forwardly and backwardly.

8. The combination with a letter-feeding carriage having ears or supports, of a rocking frame comprising a hinge-rod or rock shaft, and arms extending from said rock shaft, a platen frame connected to said arms, bushings mounted in said carriage supports, each bushing having a head provided with 25 an interior groove, ball-bearing cones upon said rock shaft to co-operate with said grooves to form raceways, and bearing balls in said raceways, means being provided including screw-threads for adjusting one of 30 said bushings in the carriage ear, so as to be capable of taking up the endwise play of the rocking frame upon the carriage.

9. The combination with a letter-feeding carriage having ears or supports, of a rocking frame comprising a hinge-rod or rock shaft, and arms extending from said rock shaft, a platen frame connected to said arms, bushings mounted in said carriage supports, each bushing having a head provided with 35 an interior groove, ball-bearing cones upon

said rock shaft to co-operate with said grooves to form raceways, bearing balls in said raceways, one of said bushings being adjustable longitudinally in the carriage ear, to be capable of taking up the endwise 70 play of the rocking frame upon the carriage, and means for clamping said bushings.

10. The combination with a letter-feeding carriage having ears or supports, of a rocking frame comprising a hinge-rod or 75 rock shaft and arms extending from said rock shaft, a platen frame connected to said arms, bushings mounted in said carriage supports, each bushing having a head provided with an interior groove, ball-bearing cones upon said rock shaft to co-operate with said grooves to form raceways, bearing balls in said raceways, and adjustable means for taking up play between the rocking frame and the carriage, said bushings being eccentrically mounted in said carriage ears and independently adjustable rotatively.

11. The combination with a letter-feeding carriage, of a rocking frame hinged thereon, a platen frame connected to said rocking frame to be controlled thereby, said carriage having ears to which said rocking frame is hinged, said rocking frame comprising a hinge-rod or rock shaft and arms extending therefrom to said platen frame, 90 means for holding the rocking frame rigidly against endwise play, while permitting free rocking movement, comprising pairs of cones upon the rock shaft, the latter having at its ends parts against which the pairs 100 of cones may be set, bushings in said carriage ears having heads provided with grooves to co-operate with the cones to form raceways, balls running in the raceways, and means to enable said bushings to be 105 spread apart to force the cones against the arms on the hinge-rod, said heads being clear of said arms.

12. The combination with a carriage and a platen frame therefor, said carriage having ears, of a rocking frame connecting the carriage to the platen frame, said rocking frame comprising a hinge-rod or shaft, arms fixed upon the ends of said shaft and connected to said platen frame, bushings 110 mounted upon the carriage ears and provided with interior grooves, balls running in the grooves, cones upon said shaft to hold the balls, said bushings being eccentrically mounted in said carriage ears and independently adjustable rotatively, and means to effect relative adjustment of said bushings to make a tight fit between the rocking frame and the carriage, said adjusting means comprising a third bushing, one 115 of said grooved bushings being enclosed in said third bushing which is threaded into the carriage ear for adjusting said grooved bushing in axial direction.

13. The combination with a carriage and 120

- 5 a platen frame therefor, said carriage having ears, of a rocking frame connecting the carriage to the platen frame, said rocking frame comprising a hinge-rod or shaft, arms fixed upon the ends of said shaft and connected to said platen frame, bushings mounted upon the carriage ears and provided with interior grooves, balls running in the grooves, cones upon said shaft to hold the 10 balls, said bushings being eccentrically mounted in said carriage ears and independently adjustable rotatively, and means to effect relative adjustment of said bushings to make a tight fit between the rocking frame and the carriage, said adjusting means comprising a third bushing, one of said grooved bushings being enclosed in said third bushing which is threaded into the carriage ear for adjusting said grooved 15 bushing in axial direction, said carriage ear being split and provided with a clamping screw, and said threaded bushing being split longitudinally to enable it to be clamped upon the grooved bushing.
- 20 25 14. The combination with a carriage and a platen frame therefor, said carriage having ears, of a rocking frame connecting the carriage to the platen frame, said rocking frame comprising a hinge-rod or rock shaft, arms fixed upon the ends of said shaft and connected to said platen frame, bushings mounted upon the carriage ears and provided with interior grooves, balls running in the grooves, cones upon said shaft to hold the balls, and means to effect relative adjustment of said bushings to make a tight fit between the rocking frame and the carriage, said adjusting means comprising a third bushing, one of said grooved bushings being enclosed in said third bushing which is threaded into the carriage ear to adjust said grooved bushing in axial direction.
- 30 35 40 45 50 55 60 65 70 75 80 85 90 95 100 105 110 115 120 125 130
14. The combination with a carriage and a platen frame therefor, said carriage having ears, of a rocking frame connecting the carriage to the platen frame, said rocking frame comprising a hinge-rod or rock shaft having bosses thereon, arms fixed upon the ends of said shaft and connected to said platen frame, bushings mounted upon the carriage ears having heads and provided with interior grooves, balls running in the grooves, cones upon said shaft to hold the balls, and means to effect relative adjustment of said bushings to make a tight fit between the rocking frame and the carriage, said carriage ears being disposed between the heads of said bushings, and said heads being disposed between the bosses on said rock shaft.
15. The combination with a letter-feeding carriage, of a rocking frame hinged thereon, a platen frame connected to said rocking frame to be controlled thereby, said carriage having ears to which said rocking frame is hinged, said rocking frame comprising a hinge-rod or rock shaft and arms extending therefrom to said platen frame, means for holding the rocking frame rigidly against endwise play, while permitting free rocking movement, comprising pairs of cones upon the rock shaft, the latter having at its ends

parts against which the pairs of cones may be set, bushings in said carriage ears having heads provided with grooves to co-operate with the cones to form raceways, balls running in the raceways, means to enable said bushings to be spread apart to force the cones against the arms on the hinge-rod, said heads being clear of said arms, said bushings being eccentrically mounted in said carriage ears and independently adjustable rotatively, and means to secure said bushings where adjusted.

16. The combination with a carriage and a platen frame therefor, of a rocking frame connecting the carriage to the platen frame, said carriage having ears, said rocking frame comprising a hinge-rod or shaft, arms fixed upon the ends of said shaft and connected to said platen frame, bushings mounted upon the carriage ears and provided with interior grooves, balls running in the grooves, cones upon said shaft to hold the balls, and means to effect relative adjustment of said bushings to make a tight fit between the rocking frame and the carriage, said adjusting means comprising a third bushing, one of said grooved bushings being enclosed in said third bushing which is threaded into the carriage ear to adjust said grooved bushing in axial direction.

17. The combination with a carriage and a platen frame therefor, of a rocking frame connecting the carriage to the platen frame, said carriage having ears, said rocking frame comprising a hinge-rod or rock shaft having bosses thereon, arms fixed upon the ends of said shaft and connected to said platen frame, bushings mounted upon the carriage ears having heads and provided with interior grooves, balls running in the grooves, cones upon said shaft to hold the balls, and means to effect relative adjustment of said bushings to make a tight fit between the rocking frame and the carriage, said carriage ears being disposed between the heads of said bushings, and said heads being disposed between the bosses on said rock shaft.

18. The combination with a carriage and a platen frame, of an intervening rocking frame hinged upon the carriage by means of units, each unit comprising a bushing having an interior groove, cones within said bushing to cooperate with said groove to form a raceway, balls in said raceway, and a tubular coupling upon which the cones are carried.

19. The combination with a carriage and a platen frame, of an intervening rocking frame hinged upon the carriage by means of units, each unit comprising a bushing having an interior groove, cones within said bushing to co-operate with said groove to form a raceway, balls in said raceway, and a tubular coupling upon which the cones

- are carried, said coupling having at one end a flange or head, and being at its other end spun or turned over upon one of the cones.
20. The combination with a carriage and a platen frame, of an intervening rocking frame hinged upon the carriage by means of units, each unit comprising a bushing having an interior groove, cones within said bushing to co-operate with said groove to form a raceway, balls in said raceway, and a tubular coupling upon which the cones are carried, one of said units also comprising an exterior longitudinally-split threaded bushing upon the grooved bushing.
- 15 21. The combination with a carriage and a platen frame, of an intervening rocking frame hinged upon the carriage by means of units, each unit comprising a bushing having an interior groove, cones within said bushing to co-operate with said groove to form a raceway, balls in said raceway, and a tubular coupling upon which the cones are carried, said coupling having at one end a flange or head, and being at its other end spun or turned over upon one of the cones, a space being left between the cones to permit the taking up of play due to wear.
22. The combination with a carriage having ears or supports, and a platen frame, of an intervening rocking frame hinged upon the carriage by means of units, each unit comprising a bushing inserted in a carriage ear and having a head provided with an interior groove, cones within said bushing to co-operate with said groove to form a raceway, balls in said raceway, and a tubular coupling upon which the cones are set, one of said units also comprising an exterior longitudinally-split threaded bushing upon the headed bushing, and said carriage ears being split and provided with clamping screws.
23. The combination of a letter-feeding carriage, a rocking frame hinged thereto, and a platen frame connected to said rocking frame to be guided thereby, said platen frame and rocking frame being of unmatched dimension and forced into co-operative relation, said rocking frame constantly tending to resume its natural form and thereby constantly tensioning against said platen frame in a direction longitudinal of the platen.
24. The combination of a letter-feeding carriage, a rocking frame hinged thereto by means of tight ball bearings, and a platen frame connected by ball bearings to said rocking frame to be guided thereby, said platen frame and rocking frame being of unmatched dimension and forced into co-operative relation, said rocking frame constantly tending to resume its natural form and thereby taking up the play in the platen-frame ball bearings and constantly tensioning said platen frame.
25. The combination of a letter-feeding carriage, a rocking frame hinged thereto by ball bearings and comprising a pair of guide arms, and a platen frame hinged to said guide arms and gripped therebetween, said platen frame being oversize, and said arms being sprung apart to accommodate the platen frame and by their reaction to exert constant pressure upon the platen frame.
26. The combination of a letter-feeding carriage, a rocking frame hinged thereto by ball bearings and comprising a pair of guide arms, and a platen frame hinged to said guide arms and gripped therebetween, said platen frame being oversize, and said arms being sprung apart to accommodate the platen frame and by their reaction to exert constant pressure upon the platen frame, said platen frame being hinged to said arms by means of ball bearings, which permit the platen frame to be gripped and tensioned by said arms while allowing free relative pivotal movement.
27. The combination of a letter-feeding carriage having ears or mounts, a rocking frame hinged to said ears by means of ball bearings, means being provided for affording adjustment of the bearings to hold the rocking frame rigidly against endwise play, said rocking frame comprising a pair of arms, and a platen frame sprung between said arms and held rigidly thereto by means of ball bearings.
28. The combination of a letter-feeding carriage, a rocking frame hinged thereto and comprising a pair of guide arms, and a platen frame hinged to said guide arms, said platen frame having ends, bearing rings provided with internal grooves fixed upon said ends, gudgeons fitted on said arms and having cones to co-operate with said grooves to form raceways, and bearing balls for the raceways.
29. The combination of a letter-feeding carriage, a rocking frame hinged thereto, a platen frame connected to said rocking frame to be guided thereby, said platen frame and rocking frame being of unmatched dimension and forced into co-operative relation, said rocking frame constantly tending to resume its natural form and thereby constantly tensioned against said platen frame in a direction longitudinal of the platen, and a platen mounted by means of ball bearings in said platen frame.
30. The combination of a letter-feeding carriage, a rocking frame hinged thereto, a platen frame connected to said rocking frame to be guided thereby, said platen frame and rocking frame being of unmatched dimension and forced into co-operative relation, said rocking frame constantly tending to resume its natural form and thereby constantly tensioned against said platen frame in a direction longitudinal of the platen.

the platen, and a platen mounted by means of ball bearings in said platen frame, means being provided for effecting relative adjustment between the ball bearings at the ends 5 of the platen for holding the platen rigidly against play in the platen frame.

31. The combination of a letter-feeding carriage, a rocking frame hinged thereto by means of ball bearings which hold the rocking frame against play in axial direction, a platen frame connected by ball bearings to said rocking frame, said rocking frame being so constructed as to maintain pressure on the platen frame in a direction longitudinal 10 of the carriage to hold the platen frame constantly under tension, and a platen mounted by means of ball bearings in said platen frame.

32. The combination of a letter-feeding carriage, a rocking frame hinged thereto by ball bearings and comprising a pair of guide arms, a platen frame hinged to said guide arms and gripped therebetween, said platen frame being oversize, and said arms being sprung apart to accommodate the platen frame and by their reaction to exert constant pressure upon the platen frame, said platen frame being hinged to said arms by means 25 of ball bearings, which permit the platen frame to be gripped and tensioned by said arms while allowing free relative pivotal movement, and a platen mounted by means of ball bearings in said platen frame.

33. The combination of a letter-feeding carriage having ears or mounts, a rocking frame hinged to said ears by means of ball bearings, means being provided for taking up any endwise play of the rocking frame between said ears, said rocking frame comprising a pair of arms, a platen frame mounted between said arms and held thereto by means of ball bearings, said rocking frame being constructed and proportioned so as automatically to prevent any endwise 40 play of the platen frame between said arms, and a platen mounted by means of ball bearings in said platen frame, means being provided for taking up any endwise play of the platen in the platen frame.

34. The combination of a carriage, a platen frame, an intervening rocking frame, comprising arms hinged upon said carriage and connected to said platen frame, said platen frame having ends, each end having 45 a hole, a ring comprising an annular bearing inserted in each hole, said ring being interiorly grooved, a set of bearing balls running in the interior groove, a pair of cones within said ring and co-operating with said interior groove to form a raceway for said balls, and gudgeons fitted to said arms and having reduced shanks extending within 55 said cones, one of the cones in each pair abutting against the body of the gudgeon,

and the other cone being confined by a flange 60 turned upon the inner end of the shank.

35. The combination of a carriage, a platen frame, an intervening rocking frame, comprising arms, hinged upon said carriage and connected to said platen frame, said 70 platen frame having ends, each end having a hole, a ring comprising an annular bearing inserted in each hole, said ring being interiorly grooved, a set of bearing balls running in the interior groove, a pair of cones 75 within said ring and co-operating with said interior groove to form a raceway for said balls, and gudgeons fitted to said arms and having reduced shanks extending within said cones, one of the cones in each pair abutting 80 against the body of the gudgeon, and the other cone being confined by a flange turned upon the inner end of the shank, a space being left between the cones to permit the taking up of play due to wear. 85

36. The combination of a carriage, a platen frame, an intervening rocking frame hinged upon said carriage and connected to said platen frame, said platen frame having ends, each end having a hole surrounded 90 with a flange, a ring comprising an annular bearing inserted in each hole, said ring having a head and being exteriorly grooved or undercut, said flange forced into said groove or undercut, said ring being interiorly 95 grooved, a set of bearing balls running in the interior groove, a pair of cones within said ring and co-operating with said interior groove to form a raceway for said balls, and means connecting said cones to said platen 100 frame.

37. The combination with a letter-feeding carriage, of a platen frame, a rocking frame hinged upon said letter-feeding carriage by means of ball bearings which hold the rocking frame tightly against endwise shake, said rocking frame pivoted to said platen frame by means of ball bearings which hold the platen frame tightly against endwise 105 shake, and a platen mounted on said platen frame. 110

38. The combination with a letter-feeding carriage, of a platen frame, a rocking frame hinged upon said letter-feeding carriage by means of ball bearings which hold the rocking frame tightly against endwise shake, said rocking frame pivoted to said platen frame by means of ball bearings which hold the platen frame tightly against endwise 115 shake, and a platen mounted on said platen frame by ball bearings which hold the platen tightly against endwise shake. 120

39. The combination with a letter-feeding carriage, of a platen frame, a rocking frame hinged upon said letter-feeding carriage by means of ball bearings which hold the rocking frame tightly against endwise shake, said rocking frame pivoted to said platen 125 frame.

frame by means of ball bearings which hold the platen frame tightly against endwise shake, the platen frame and the rocking frame being so constructed and proportioned that the platen frame will be held constantly under pressure by the rocking frame, and a platen mounted on said platen frame.

40. The combination of a platen having an axle, a platen frame having ends, bearing rings fixed in said ends, each of said bearing rings having a groove, pairs of cones through which the platen axle extends, tubes on the platen axle within said pairs of cones, said pairs of cones being confined upon said tubes and co-operating with the grooves in the bearing rings to form raceways, and bearing balls in the raceways.

41. The combination of a platen having an axle, a platen frame having ends, bearing rings fixed in said ends, each of said bearing rings having a groove, pairs of cones through which the platen axle extends, tubes on the platen axle within said pairs of cones, said pairs of cones being confined upon said tubes and co-operating with the grooves in the bearing rings to form raceways, and bearing balls in the raceways, each of said tubes having a head at one end and spun over at the other end to take up play of the balls.

42. The combination of a platen having an axle, a platen frame having ends, bearing rings fixed in said ends, each of said bearing rings having a groove, pairs of cones through which the platen axle extends, tubes on the platen axle within said pairs of cones, said pairs of cones being confined upon said tubes and co-operating with the grooves in the bearing rings to form raceways, and bearing balls in the raceways, each of said bearing rings having a head within the platen frame, and said platen frame having openings into which said bearing rings are forced.

43. The combination of a platen having an axle, a platen frame having ends, bearing rings fixed in said ends, each of said bearing rings having a groove, pairs of cones through which the platen axle extends, tubes on the platen axle within said pairs of cones, said pairs of cones being confined upon said tubes and co-operating with the grooves in the bearing rings to form raceways, and bearing balls in the raceways, each of said bearing rings having a head within the platen frame, and said platen frame having openings into which said bearing rings are forced, each opening formed with a flange or brim to afford a support for the body of the bearing ring.

44. The combination of a platen having an axle, a platen frame having ends, bearing rings fixed in said ends, each of said

bearing rings having a groove, pairs of cones through which the platen axle extends, tubes on the platen axle within said pairs of cones, said pairs of cones being confined upon said tubes and co-operating with the grooves in the bearing rings to form raceways, and bearing balls in the raceways, said platen having a head and a threaded bushing therefor, adjustable to take up endwise play of the platen.

45. The combination of a platen having an axle, a platen frame having ends, bearing rings fixed in said ends, each of said bearing rings having a groove, pairs of cones through which the platen axle extends, tubes on the platen axle within said pairs of cones, said pairs of cones being confined upon said tubes and co-operating with the grooves in the bearing rings to form raceways, bearing balls in the raceways, said platen having a head and a threaded bushing therefor, adjustable to take up endwise play of the platen, and fillers or spacing washers inserted between said threaded bushing and the end of the platen.

46. The combination of a platen frame having ends provided with holes, headed bearing rings forced into said holes, the heads being on the inside of the platen frame ends, said rings having interior grooves, cones encircled by said rings and co-operating with said grooves to form raceways, balls in said raceways, and means coupling the cones together and confining them permanently within said rings.

47. The combination of a platen frame having ends provided with holes, headed bearing rings forced into said holes, the heads being on the inside of the platen frame ends, said rings having interior grooves, cones encircled by said rings and co-operating with said grooves to form raceways, balls in said raceways, and means coupling the cones together and confining them permanently within said rings, said coupling means comprising tubes, each having a head at one end and spun over at the other end to confine the cones.

48. The combination with a platen, of a platen frame having ends provided with holes, headed bearing rings forced into said holes, the heads being on the inside of the platen frame ends, said rings having interior grooves, cones encircled by said rings and co-operating with said grooves to form raceways, balls in said raceways, and means coupling the cones together and confining them permanently within said rings, said coupling means comprising tubes, each having a head at one end and spun over at the other end to confine the cones, a platen axle extending through said cones, said platen having at one end a part which is adjustable to vary the length of the part of the platen

surrounding the platen axle to cause the platen to fit tightly between the pairs of cones.

49. The combination of a letter-feeding carriage, a platen frame, and means mounted upon said carriage to guide said platen frame in case-shift movements, said platen frame provided at its ends with two forward feet to rest upon the carriage, and provided at 10 its rear with a foot midway of its ends, to rest upon the rear of the carriage.

50. The combination of a letter-feeding carriage, a platen frame, and means mounted upon said carriage to guide said platen frame in case-shift movements, said platen frame provided at its ends with two forward feet to rest upon the carriage, and provided at 15 its rear with a foot midway of its ends, to rest upon the rear of the carriage, 20 the platen frame having bendable portions to enable said three feet to be brought to proper positions upon the carriage.

51. The combination of a platen, a letter-feeding carriage, a rocking frame hinged thereto, a platen frame pivoted to said rock-

ing frame, a lift rail for said platen frame, feet on the ends of the platen frame to support the forward portion thereof upon the carriage, and a foot midway of the platen frame to support the rear of said platen frame upon said carriage.

52. The combination with a letter-feeding carriage having ears, of a rocking frame comprising a hinge-rod or rock shaft and arms extending from said rock shaft, a 35 platen frame connected to said arms, bushings mounted in said carriage ears and provided with interior grooves, cones upon said rock shaft to co-operate with said grooves to form raceways, bearing balls in said raceways, said bushings being eccentrically mounted in said carriage ears and independently adjustable rotatively, and means for effecting relative adjustment of said bushings to make a tight fit between the rocking 40 frame and the carriage for taking up play.
